UNITED STATES PATENT OFFICE.

WILLIAM M. BROOKE, OF BROOKLYN, ASSIGNOR TO HIMSELF, AND GEORGE W. MARTIN, OF NEW YORK, N. Y.

PERMUTATION-PADLOCK.

SPECIFICATION forming part of Letters Patent No. 465,450, dated December 22, 1891.

Application filed February 28, 1891. Serial No. 383,271. (No model.)

To all whom it may concern:

Be it known that I, WILLIAM M. BROOKE, of Brooklyn, in the county of Kings and State of New York, have invented certain new and useful Improvements in Permutation-Locks, of which the following is a full, clear, and exact description.

My invention relates to permutation-locks; and the object of my invention is to improve the construction of such locks.

To this end my invention consists of certain features of construction, and combination of parts, which will be hereinafter described and claimed.

Reference is to be had to the accompanying drawings, forming a part of this specification, in which similar letters of reference indicate corresponding parts in all the figures.

Figure 1 is a perspective view showing my improved lock in the locked position. Fig. 2 is a central vertical section of the same. Fig. 3 is a side elevation of the staple with a portion of one member broken away to show the swinging toothed bar, and Fig. 4 is a plan view of the cover-plate.

The case A of the lock is divided into two compartments and is open at one side of one compartment. The larger A² of the compartments contains the numbered tumblers B and is closed at the top by a sliding cover-plate B' and the smaller A' receives one member of the locking-staple. The compartment A' is provided at the top with an annular inwardly-extending rim or shoulder a', the opening through which is of a size to loosely fit the member of the locking-staple received in the compartment. The cover-plate B' (see Fig. 4) is essentially semicircular in form, and is held in a groove b' in the wall of the compartment A² near the top thereof. The plate is apertured at b² for the passage of one member of the locking-staple. The tumblers B have central openings to receive one member of the locking-staple and have transverse openings b leading from the central opening, so that when the transverse openings align the locking-staple may be withdrawn. The staple C is reduced near the ends, the reduced portion corresponding in length to the inside length of the lock-case, one member C' being adapted to enter the compartment

A² and the openings in the tumblers B and the opposite member C' being adapted to enter the compartment A'. The member C' is slotted longitudinally, and pivoted in the slot near the extreme end is a bar E, which extends longitudinally through the slot. The bar E is provided with laterally-extending teeth e, adapted to engage the tumblers and prevent the withdrawal of the staple. The toothed bar E is pivoted at one end, as shown at e', and the opposite end is slotted and held to slide laterally on a pin e², which holds it in place in the slot of the member C'. It will be observed that the teeth e are inclined toward the free end of the member, so that they may be easily inserted through the opening in the tumblers; but the opposite sides of the teeth are abrupt and at right angles to the bar E, so that they will engage the tumblers and hold the bar and the staple in place. A bentspring F is secured to the back of the bar E and is arranged so that it will normally project from the side of the member C'. This spring will yield sufficiently so that the member C' of the staple may be inserted through the tumblers without the trouble of making the transverse slots b of the tumblers align, as the spring will yield and allow the bar E to swing into the slot, so that the teeth will not project from the member C'; but after the teeth have passed the inner edges of the tumblers the spring will cause the bar to swing, so that the teeth will engage the tumblers, and the staple cannot be withdrawn until they are turned so as to make the slots b align with the teeth e. The member C² of the staple which enters the compartment A' of the lock-case is provided with a spring-catch G, which is secured to it at a point adjacent to the outer end of the lock-case, and the spring is doubled to form a shoulder g, which engages the shoulder a' in the lock-case, and thus prevents the accidental removal of the staple; but the bore of the compartment A' may be of a size to only loosely receive the staple member, and a recess may be provided in the wall of the compartment to receive the shoulder of the spring. The catch G is also bent so as to extend outward through the end of the case, and its extreme end g' is bent outward, so that it may

be easily operated by the finger. To permit of the necessary lateral movement of the catch, the member C^2 is recessed opposite the catch, as shown at c' , so that to release the catch 5 from the shoulder a' it is merely needful to press inward on the free end g' , which thus disengages the shoulder g from engagement with the shoulder a' .

When the lock is suspended—as upon a 10 car-door, for instance—the continual jolting of the car will sometimes cause the tumblers B to turn, so that the slots b will align, and in this case the lock-case would fall from the staple if it were not for the catch G ; but this 15 prevents the removal of the staple, and the tumblers will soon turn out of alignment, so that no harm is done. When the locking-staple is removed from the lock, the cover-plate B' can be easily removed and the combination changed; but when the locking-staple 20 is in place the cover is held and access cannot be had to the tumblers.

To insert the staple and fasten the lock, it is only needful to push the member C' in 25 through the tumblers regardless of their position and the member C^2 into the compartment A' , when the teeth e engage the tumblers and hold the staple securely in place. To remove the staple, the tumblers are turned 30 until the slots b align with the teeth e , when by simply pressing inward on the catch G the staple may be removed.

As a precaution against the lock-case and staple becoming separated, a chain D is secured 35 to a perforated ear a on one end of the lock-case and to a similar ear c on the staple C .

Having thus described my invention, what I claim as new, and desire to secure by Letters Patent, is—

1. In a permutation-lock, the combination, 40 with the tumblers, the lock-staple, and the case having its tumbler-holding compartment open at the top and provided with an internal groove, of an apertured cover-plate, substantially as described. 45

2. A lock comprising a two-part case, one compartment of which is open at one side and at the top and is provided with a series of tumblers and the other of which is provided with an internal shoulder, and a staple to enter the case, said staple having one member provided with teeth to engage the tumblers and the other with a spring-catch to engage the internal shoulder, substantially as described. 50

3. In a lock-case which is divided into two compartments, one of which is open at the top, provided with a groove in its wall, and adapted to receive tumblers, and the other of which is provided with an internal shoulder, 60 the combination, with said case, of an apertured cover-plate and a locking-staple having teeth on one member and a locking-spring on the other member, substantially as shown and described. 65

4. The combination, with the two-part lock-case, one compartment of which is provided with tumblers and the other with a shoulder, of a staple adapted to enter the case, one member of the staple having teeth to engage 70 the tumblers and the opposite member having a spring-catch to engage the shoulder, substantially as shown and described.

WILLIAM M. BROOKE.
